UNITED STATES PATENT OFFICE

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

ACETYLENE-LAMP.

1,165,969.

Specification of Letters Patent. Patented Dec. 28, 1915.

Application filed March 5, 1915. Serial No. 12,295.

To all whom it may concern:

Be it known that I, AUGIE L. HANSEN, a citizen of the United States, and a resident of Evanston, in the county of Cook and State of Illinois, have invented certain new and useful Improvements in Acetylene-Lamps, of which the following is a specification.

My invention relates to acetylene lamps, 10 and particularly to miners' lamps. Lamps of this class usually comprise a water container, a carbide cup and a burner and reflector, and one of the important objects of my invention is to provide such compact 15 and otherwise improved arrangement of these parts as will particularly adapt the lamp for miners and will cause it to more efficiently direct the light to the work.

Another feature of my invention is particularly adaptable where the burner is 20 associated with the carbide cup and such cup is detachable from the water container in order to be replaced when the carbide becomes exhausted, the feature involving improved valve mechanism for automatically connecting the water supply with the carbide when the carbide cup is attached to the water container, and for automatically closing the cup when the cup is removed in order 25 that the final gas supply from said cup can be utilized for illuminating purposes while a cup with a fresh charge is secured to the water container.

Another object is to provide a strong and 30 compact carbide cup structure and improved arrangement of a combined burner, reflector and gas cleaning structure in connection therewith.

The invention also involves other features 35 of construction and arrangement all of which assist in producing simplicity and compactness, and ready accessibility to all parts for inspection, cleaning and repairs.

On the accompanying drawing I have 40 shown a lamp embodying the various features of the invention and Figure 1 is a side elevational view of a lamp showing it in place on a miner's cap, Fig. 2 is a top view of the lamp, Fig. 3 is a sectional view 45 on plane 3-3, Fig. 2, and Fig. 4 is a sec-

tional view on plane 4-4, Fig. 3, with parts broken away to reveal the interior arrangement.

A convex or dome shaped frame 10 supports the inverted cup-shaped frame 11, 55 these two parts forming the water container W. As shown, a hook member 12 and a clip member 13 are secured to one side of the container for engaging with the top and vertical sections *a* and *b* of the supporting frame F which is secured to a cap C, such engagement being in the usual well known manner. Extending vertically through the water container between the bottom frame 10 and the top wall thereof is the vertical 60 water duct 14 having the inlet slit 15. Secured to the under side of the wall 10 opposite the lower end of the duct 14 is the coupling member 16 whose reduced end 17 extends into the duct 14 through the opening 18 in the wall 10. Through the coupling member extends the axial passageway 19 which at its inner end is flared to form the conical valve seat 20 for the valve stem 21 which extends through the water 65 duct 14. At its upper end the water duct is internally threaded to receive the threaded upper end 22 of the stem so that turning of the stem one way or the other will cause its conical end *e* to open or close the passageway 19 to the duct 14 and the water container. A lever 23 is secured to the upper 70 end of the stem and has a spring latch 24 for co-operating with the detent projections 75 formed in the upper wall of the water container. The upper wall of the water container has also the water supply inlet 26 80 for which a plug 27 is provided.

Describing now the carbide container G, the body 28 of this container is cup-shaped 90 with a convex bottom and its outer edge section 29 is threaded for receiving the cover structure 30. Extending axially through the cup 28 from the bottom thereof is a valve barrel 31 whose outer end provides the 95 threaded socket 32 for receiving the threaded coupling member or plug 16 which extends from the water container, this coupling engagement serving to secure the carbide container to the wall 10 and when thus 100

secured the convex bottom of the cup fits into the dome 10 in very compact arrangement, and when the lamp is hung on the cap frame F the water container will be disposed horizontally and the axis of the carbid container will be at an angle with the horizontal, and such axis will be substantially parallel with the vizer v of the cap.

The inner end of the barrel 31 forms the 10 valve chamber 33 for the check valve 34, and the wall 35 between the valve chamber and the socket 32 has the inlet opening 36 whose inner edge is beveled to form the seat 37 for the valve 34. A spring 38 encircling 15 the valve stem 39 between the valve and the removable cap 40 for the barrel tends to hold the valve against its seat to close the inlet opening, the barrel having longitudinal water passageways or slits 41 connecting 20 the valve chamber with the interior of the carbid cup. An extension 42 on the valve projects through inlet opening 36 and is of less cross section area than said opening. The outer end 43 of the coupling 25 member or plug 16 is of reduced diameter and forms an abutment for the projection 42 when the carbid container is secured to the water container. When the carbid container is removed the spring 38 will cause 30 the valve to close the water inlet opening 36, but when the container is screwed to the member 16 the valve projection will encounter the end 43 and the valve will be shifted away from its seat to effect connection 35 of passageway 19 with the valve chamber and the carbid cup, the end 43 being provided with radial slits or passageways 44 for the passage of water when the extension 42 abuts against the end 43. When 40 the two containers are coupled together and the valve stem 21 is turned to open passageway 19 to the water container, water will flow through this passageway and passageway 36 and through slits 41 into the carbid cup and gas will be generated. Upon 45 uncoupling of the containers the spring 38 will cause valve 34 to close the water inlet 36 to seal the carbid container against escape of gas through such inlet. Fingers 45 are projected from the valve through the passageways 41 and when the valve is shifted during coupling of the containers these fingers will clean the passageways of any 50 accumulations of carbid and the valve extension 42 moving in the inlet passageway 36 will clean this passageway of any accumulations in order that water may then freely flow from the water container to the carbid container.

55 The cover structure 30 already referred to is deflected inwardly or concaved and has the threaded flange 30' for engaging the threaded end of the carbid cup, a washer 46 being inserted between the cover and the

cup to insure sealing fit. Extending axially and secured to the cover is the block 47 having the threaded socket 48 for receiving the threaded inner end of the burner frame 49 which extends axially through and is secured to the concave reflector 50. 70 The reflector with the deflected part of the cover 30 forms a chamber 51 interposed between the carbid cup and the burner frame, the cover being provided with small gas outlets 52 and the burner frame having the 75 radial inlets 53 to its central passage 54 which passage communicates with the tip 55 seated in the outer end of the burner frame. To insure sealing a suitable washer 56 is interposed between the reflector and 80 the cover 30.

In order to filter and clean the gas before it reaches the burner, filtering material 57 is provided, this filtering material surrounding the burner inlets between the 85 cover and reflector, being, as shown, confined within a circular flange 58 extending from the reflector to within a short distance of the cover. With this arrangement, the gas before reaching the burner, 90 must work its way through the filter material.

The lamp described is very compact and particularly adaptable for miners' use, the angular arrangement of the carbid container 95 causing the rays of light to be projected onto the work in front of the miner. The arrangement is such that the lamp can be readily and accurately controlled and kept in the best working condition. When the 100 carbid in one container is almost exhausted, another container can be substituted, and such substitution can be made by the light of the removed container. The valve mechanism which is automatically controlled upon coupling of the carbid container to the water container keeps the water passages clear. The generated gas before reaching the burner is filtered and the heavier particles will fall to the bottom of 110 chamber 51 to be expelled when the reflector is removed from the cover 30. To facilitate removal of the cover from the reflector structure when it is desired to refill the carbid cup radial projections 59 are 115 provided on the flange 30' of the cover, these projections, as shown, being in the form of loops in a band 60. In order to strengthen the cup its convex end may be corrugated as indicated at 61. As the carbid in the cup is apt to become caked it is customary for the miner to tap the cup against his heel or a wall. However, the corrugations will protect the thin sheet metal against bending and indenting. The 120 corrugations also facilitate coupling and uncoupling of the carbid container and water container. In order to guide the carbid

cup into coupling position, guide ears 62 are extended downwardly from the sides of the water container.

I do not of course desire to be limited 5 to the precise construction and arrangement shown and described, as changes and modifications are no doubt possible which would still come within the scope of the invention.

10 I claim the following:

1. In an acetylene lamp, the combination of a water container, supporting means thereon for adapting it for suspension in vertical position on a miner's cap, a carbide 15 container adapted for detachable connection with the bottom of said water container to extend diagonally therefrom substantially parallel with the vizor of a cap, a burner extending from the lower end of the carbide 20 container, and a reflector at the lower end of said carbide container for throwing the light diagonally downwardly.

2. In a miner's acetylene lamp, the combination of a water container, means thereon adapting it for suspension in vertical position on a miner's cap, a carbide container in the form of an inverted cup secured at its base to the base of the water container with its axis extending diagonally and substantially 30 parallel with the vizor of a cap, means controlling the flow of water from the water container to the carbide container, a reflector structure closing the mouth of said carbide container, and a burner carried by the reflector structure, said reflector throwing the light diagonally downwardly in the direction of the carbide container axis.

3. In a miner's acetylene lamp, the combination of a water container adapted to be 40 suspended from a support with its axis vertical and having its bottom wall domed inwardly to form a pocket, a carbide container in the form of an inverted cup with a convex base adapted to fit said pocket, means 45 for detachably securing said carbide container in the pocket of the water container with its axis diagonal with respect to the water container axis, means controlling the flow of water from the water container to 50 the carbide container when the containers are secured together, a reflector structure forming a cover for said carbide cup, and a burner mounted on said reflector structure to have its light thrown diagonally downwardly.

55 4. In a miner's acetylene lamp, the combination of a water container adapted to be suspended from a support with its axis vertical and having its bottom wall deflected inwardly to form an external spherical 60 pocket, a carbide container in the form of an inverted cup with a convex bottom for fitting said pocket, said carbide cup being inclined with its axis extending diagonally to cause the mouth of the carbide cup to point

diagonally downwardly, a coupling for detachably securing the containers together, said coupling having a passageway, valve mechanism for controlling the flow of water through said passageway from the water container to the carbide container, a concave 70 reflector detachably secured to close the mouth of said carbide container with its axis coincident with that of the carbide container, and a burner secured in said reflector at the axis thereof to have its light reflected diagonally downwardly.

5. In a miner's acetylene lamp, the combination of a water container adapted to be supported with its axis vertical and having its bottom wall deflected inwardly to form 80 an external pocket, a coupling member extending diagonally into said pocket from one side thereof, a cup-shaped carbide container having a convex bottom for fitting into said pocket, a companion coupling 85 member secured to the carbide container bottom and extending axially therethrough and adapted for connection with the coupling member on said water container to connect the carbide container thereto with its axis 90 extending diagonally, said coupling having a water passageway therethrough, main valve mechanism on said water container for controlling the flow of water to said passageway, auxiliary valve mechanism within 95 said carbide container for closing said passageway when the containers are disconnected and for automatically opening said passageway to the carbide container when the containers are connected, a reflector 100 structure forming a cover for the carbide container, and a burner mounted on said reflector structure and extending coincident with the carbide container axis whereby the light is deflected diagonally downwardly by 105 the reflector structure.

6. In a miner's acetylene lamp, the combination of a water container adapted to be supported in vertical position, a carbide container in the form of a cup, means for detachably securing said containers base to base and with the carbide container extended diagonally downwardly, means for controlling the water flow from the water container to the carbide container, a detachable main 110 cover for closing the mouth of said carbide container, a reflector detachably secured to said cover to form a chamber therewith, a burner mounted on said reflector and extending into said chamber to receive gas 115 therefrom and said cover having gas ports therethrough, said reflector being at right angles to the axis of the carbide container in order to throw the light diagonally downwardly.

7. In a miner's acetylene lamp, the combination of a cylindrical water container adapted to be supported in vertical position,

- a cylindrical cup-shaped carbide container, means detachably securing said containers together base to base with the axis of the carbide container extending diagonally, valve
5 mechanism for controlling the flow of water from the water container to the carbide container, a main cover for closing the mouth of the carbide container, a threaded axially extending socket on said cover, a reflector
10 having a threaded axially extending tube adapted for engaging in said socket to se-

cure the reflector to the cover, and a burner tip in the outer end of said tube, said reflector deflecting the light diagonally downwardly.

15

In witness whereof I have hereunto set my hand this 27th day of February, A. D. 1915.

AUGIE L. HANSEN.
